GAS STOVE

André Traclet, Chaponost, France, assignor to
Application des Gaz, Paris, France

Filed Feb. 16, 1971, Ser. No. 115,912

Term of patent 14 years

Int. Cl. D7—02

U.S. Cl. D81—10

Fig. 1

Fig. 3

Fig. 5

Fig. 4

Fig. 2

Fig. 6

Fig. 8

Fig. 10

Fig. 9

Fig. 7

FIG. 1 is a front view of gas stove showing my new design.

FIG. 2 is an underside view thereof.

FIG. 3 is a side view thereof.

FIG. 4 is a top view thereof.

FIG. 5 is a rear view thereof.

FIGS. 6 to 10 are the same views as FIGS. 1 to 5, but showing the stove at the opened position.

I claim:

The ornamental design for a gas stove, as shown.
